UNITED STATES PATENT OFFICE

THOMAS J. STINSON, OF HARTFORD, CONNECTICUT

CLEANING COMPOSITION

No Drawing.

Application filed August 20, 1924. Serial No. 733,195.

This invention relates to the art of cleaning materials, and more particularly to a new and improved composition of matter therefor.

It is a particular object of this invention to provide a cleaning composition which may be distributed either as a liquid, powder or paste, and which will be efficient for washing fabrics of all kinds and removing stains therefrom, for cleaning floors and other articles of wood or composition materials, and for washing the hands without the use of water.

One of the difficulties present in other cleaning compositions intended for washing, such as those in which borax or ammonia is used, is that they remove the color from colored fabrics.

It is therefore a further object of this invention to provide a cleaning composition which will accomplish the above objects without affecting the color of colored fabrics or of injuring the substance being cleaned, irrespective of whether this substance be fabric, woodwork, composition flooring or the skin.

The ingredients used in making my cleaning composition are chloride of lime, vinegar, water, and the commercial product known as Prosperity soda.

The chloride of lime CaOCl_2 is preferably used in the form of a powder. The vinegar may be cider vinegar or white wine vinegar, or a mixture of the two. I have found it preferable to use Prosperity Blue Label soda because this does not injure the skin. However, Prosperity Red Label soda will produce a satisfactory cleaning composition although it is somewhat harsh on the skin. In order that my invention may be defined with sufficient definiteness to enable any person skilled in the art to make and compound it, I set forth below the analyses of these two types of Prosperity soda:

Blue label	Per cent	Red label	Per cent
Sodium carbonate.....	44.52	Sodium carbonate.....	39.75
Sodium bicarbonate.....	42.00	Sodium bicarbonate.....	45.36
Sodium chloride and sodium sulphate.....	.58	Sodium chloride and sodium sulphate.....	.43
Ammonium sulphate.....	2.18	Ammonium sulphate.....	.11
Insoluble.....	.05	Insoluble.....	.10
Moisture.....	10.67	Moisture.....	14.25
Total.....	100.00	Total.....	100.00

In the preparation of my improved clean-

ing composition I use the ingredients referred to above in the proportions and manner indicated below:

Liquid form. Two and one-half pounds of chloride of lime are poured into two and one-half gallons of water and allowed to stand. At the same time, two and one-half pounds of Prosperity Blue Label soda are dissolved independently in two and one-half gallons of water. The two solutions are then stirred together and the resulting mixture is allowed to stand for about twelve hours. One-half pint of cider vinegar is then stirred into the mixture, after which the clear liquid is strained off and the sediment is discarded. The clear liquid is then ready for use.

Powdered form. One-half pint of cider vinegar is added to two and one-half pounds of Prosperity Blue Label soda. This is allowed to dry and two and one-half pounds of chloride of lime are added to the mixture, which is then ready for distribution. When it is desired to use it, it is only necessary to add hot water, stir, allow it to settle, and pour off the clear liquid into any convenient container.

Paste form. The liquid form is prepared as indicated above and one quart of it is heated until it comes to a boil. One-half pound of chip soap (88% pure) is added to two cups of cold water and this mixture is poured into the hot liquid. The resulting mixture is stirred until the soap is dissolved, after which the composition is poured into the containers in which it is to be distributed and allowed to set, whereupon it assumes a pasty consistency. In using the paste form of my composition it is only necessary to rub a small quantity of it on the hands, to loosen the dirt and grime, and then wipe the hands clean on a piece of cloth.

It will be understood that soap is not required for the liquid or powdered forms of my invention, and that its use in the paste form serves the double purpose of providing a vehicle for the convenient use of my composition, when water is not available,

and at the same time facilitates the removal of the dirt.

The composition produced as indicated above is highly efficient as a cleaning composition and is particularly useful in wash-

5 ing clothes, both white and colored, inasmuch as it facilitates the removal of the dirt without any deleterious effect on the colors. In other words, the addition of the
10 vinegar sets the colors.

It will also be understood that the proportions indicated above may be varied within reasonable limits, that white wine vinegar may be substituted for part or all of the
15 cider vinegar, and that the Prosperity Red Label soda may be substituted for the Prosperity Blue Label soda. Furthermore, if desired, the commercial Prosperity soda may be replaced by a compound formed by mix-
20 ing together sodium carbonate, sodium bicarbonate, sodium chloride, sodium sulphate, and ammonium sulphate in such proportions as to produce a compound having approximately the percentage composition set
25 forth above for either of the commercial Prosperity sodas. Furthermore, if desired, other equivalents may be used for the substances set forth above.

I claim:

30 1. A cleaning composition formed by mixing chloride of lime, Prosperity soda and vinegar in substantially the proportion of two and one-half pounds of chloride of lime, two and one-half pounds of Prosperity soda,
35 and one-half pint of vinegar.

2. A cleaning composition formed by mixing chloride of lime, Prosperity soda, vinegar and water in substantially the proportion of two and one-half pounds of chloride
40 of lime, two and one-half pounds of Prosperity soda, and one-half pint of vinegar to five gallons of water.

3. A cleaning composition formed by mixing chloride of lime, vinegar, and a compound containing sodium carbonate, sodium bicarbonate and ammonium sulphate in substantially the proportion of two and one-half pounds of chloride of lime, two and one-half pounds of the compound, and one-
50 half pint of vinegar, the sodium carbonate, sodium bicarbonate and ammonium sulphate constituting at least 85% of the compound which is mixed with the chloride of lime and the vinegar.

55 4. A cleaning compound formed by mixing substantially equal quantities of chloride of lime and Prosperity soda, and a substantial, but materially smaller, quantity of vinegar.

60 5. A cleaning compound formed by mixing substantially equal quantities of chloride of lime and Prosperity soda (a substantial, but materially smaller, quantity of vinegar, and water.

65 6. A cleaning compound formed by mix-

ing substantially equal quantities of chloride of lime and Prosperity soda, a substantial, but materially smaller, quantity of cider vinegar, and water.
